DESIGN FOR A TEXTILE FABRIC OR THE LIKE

Armin W. Baldegger, Union City, N. J.

Application October 20, 1934, Serial No. 53,703

Term of patent 3½ years

To all whom it may concern:

Be it known that ARMIN W. BALDEGGER, a citizen of the United States, residing at No. 612 23d Street, Union City, county of Hudson, New Jersey, have invented a new, original, and ornamental Design for a Textile Fabric or the like, of which the following is a specification, reference being had to the accompanying drawing, forming a part thereof.

The figure is a plan view of a textile fabric showing my new design.

The cross-hatching appearing on the drawing represents a substantial solid background. The arbitrary figures are embroidered upon this substantial solid background, the center portion being cut out and in which the outline of a star is embroidered.

I claim:

The ornamental design for a textile fabric or the like as shown and described.

In testimony whereof I have signed this specification.

ARMIN W. BALDEGGER.
